(57) **CLAIM**

The ornamental design for a combined barbecue and patio heater, as shown and described.

DESCRIPTION

FIG. 1 is a perspective view of a heater of the present invention with the combined barbecue and patio heater shown in a closed condition;

FIG. 2 is a right side view thereof;

FIG. 3 is a front view thereof;

FIG. 4 is a top view thereof;

FIG. 5 is a left side view thereof;

FIG. 6 is a rear view thereof; and,

FIG. 7 is a perspective view thereof with the combined barbecue and patio heater shown in an open condition.

The bottom plan view forms no part of the claimed design.

1 Claim, 7 Drawing Sheets
